(57) **CLAIM**

The ornamental design for an apparatus assembly for receiving cones and fill as shown and described.

DESCRIPTION

FIG. 1 is an assembled top perspective view of the apparatus assembly for receiving cones and fill, showing our new design;

FIG. 2 is an exploded view with the upper portions removed from the assembly for clarity of disclosure;

FIG. 3 is an assembled side view thereof;

FIG. 4 is an assembled front view thereof; and,

FIG. 5 is an assembled top view thereof.

The evenly spaced broken lines, including the areas within them, depict portions of the apparatus assembly for receiving cones and fill that form no part of the claimed design.
